No. 36,509.

Patented August 18, 1903.

UNITED STATES PATENT OFFICE.

CHARLES SCHWARCZ, OF NEW YORK, N. Y., ASSIGNOR TO THE CASTLE BRAID COMPANY, A CORPORATION OF NEW YORK.

DESIGN FOR BRAID.

SPECIFICATION forming part of Design No. 36,509, dated August 18, 1903.

Application filed July 10, 1903. Serial No. 165,035. Term of patent 7 years.

To all whom it may concern:

Be it known that I, CHARLES SCHWARCZ, a citizen of the United States, residing at the city of New York, in the borough of Manhattan and State of New York, have invented a new, original, and ornamental Design for Braid, of which the following is a full, clear, and exact description.

The drawing is a face view of the braid, showing my new design.

I claim—

The ornamental design for braid, as shown. In witness whereof I subscribe my signature in presence of two witnesses.

CHARLES SCHWARCZ.

Witnesses:

WALDO M. CHAPIN,
WM. A. ROSENBAUM.
